COMBINED IRONING BOARD AND SEAT UNIT

Claire B. Glassie and Donelson C. Glassie,
Washington, D. C.

Application April 25, 1952, Serial No. 19,472

Term of patent 14 years

(Cl. D49—1)

To all whom it may concern:

Be it known that we, Claire B. Glassie and Donelson Caffery Glassie, citizens of the United States, residing in Washington, District of Columbia, have invented a new, original, and ornamental Design for Combined Ironing Board and Seat Unit, of which the following is a specification, reference being had to the accompanying drawing, forming a part hereof.

Figure 1 is a side elevation of a combined ironing board and seat unit, showing our new design, and

Figure 2 is a top plan view of Figure 1.

The dominant features of my design reside in those portions shown in full lines.

We claim:

The ornamental design for a combined ironing board and seat unit, as shown and described.

CLAIRE B. GLASSIE,
DONELSON CAFFERY GLASSIE.
